COLLAPSIBLE CANOE

Oscar Valdemar K. Hald, St. Catharines,
Ontario, Canada

Application December 29, 1933, Serial No. 704,374

2 Claims.

The invention relates to improvements in collapsible canoes as described in the present specification and shown in the accompanying drawings that form part of the same.

5 The invention has for its object the production of a canoe composed of a water-proof canvas covering and a skeleton framework of a readily collapsible nature that will fold into a minimum of space when not required or for transportation purposes. This is attained by a framework of ribs connected one to another by a keel and side members designed to fold inwardly in order that the ribs may come together. The bows are adapted to fold against the respective adjoining 10 ribs, so that the entire framework occupies but little space and the complete canoe when folded makes a portable package transportable by motor car.

20 A distinct feature of construction resides in the provision of an inflatable floor mat that prevents the canoe from sinking in the event of its capsizing.

25 Referring to the accompanying drawings Figure 1 is a side elevation of the canoe partly in section in order to illustrate to better advantage the framework.

30 Figure 2 is a plan view thereof with a part of the inflatable mat broken away.

Figure 3 is a plan view of the inflatable mat. Figure 4 is a cross section thereof.

35 Figure 5 is a perspective view illustrating a rib and its connection with the keel and side members. This view is typical of the connection of the keel and the side members with the ribs, and shows the framework unfolded.

Figure 6 is a perspective view of a fragmentary part of the frame partly folded.

40 Figure 7 is a sectional view showing the side members of the frame, illustrated in Figure 6, completely folded. This view also serves to typify the folding of the keel.

Figure 8 is a section taken on line 8—8 of Figure 5.

45 Figure 9 is a sectional view of a rib showing the inward folding of the side and keel parts.

Figure 9A is a detail of an upper end of a rib typifying the pivotal connection for the side pieces.

50 Figure 10 is a longitudinal section of the bow portion of the frame.

Figure 11 is a cross section taken on line 11—11 of Figure 10.

55 Figure 12 is an elevation of the oar. Like numerals of reference indicate corre-

Each two bars that are connected to a rib are provided with a locking arrangement similar to the keeper aforesaid, i. e., the adjacent ends of the bars are slotted as at 29, 29' on the inner side and a keeper 30 is pivoted in the slot 29 so as to swing into engagement with the slot 29'. This not only locks the adjoining bars of two adjoining side members in alignment, but also enables them to swing inwardly when the keeper is disengaged. 10 As the side members are folded inwardly the ribs are brought together as illustrated in Figure 6.

The keel 31 is composed of members similar in construction and operation to the side members above recounted. A keel member extends between 15 each two adjoining ribs and is pivoted thereto and composed of a pair of bars 32 joined at their meeting ends by a link. The link allows the bars to fold upwards one against the other and when unfolded they may be locked by a keeper 34. 20 Each two adjoining bars that are pivoted to the ribs have a keeper 35 to lock them in unfolded relation. In order to form a floor the keel members are supplied with transverse treads 36 rigidly secured and disposed between the ribs to cooperate 25 therewith in sustaining the mat aforesaid.

The bow parts of the keel are each composed of two sections 37 and 37' pivotally attached by a link 38 that enables them to fold together, while a keeper 39 is pivoted to the section 37 and has a 30 U-shaped portion 40 that fits over the link connection in order to secure the component parts of the bow in unfolded relation. The section 37 is pivotally attached at 41 to the end rib so as to fold inwardly thereagainst. The free terminus 42 of 35 the other section however has a pair of detachable wire rods 42' connecting it to the upper ends 43 of the end rib.

It will be manifest from the preceding description that the framework when unfolded and secured by the locking elements produces a light and sturdy structure, which when covered by the canvas provides a serviceable canoe, the mat of which precludes sinking in the case of its upset-

45

50

55

60

65

70

75

ting. Furthermore it will be seen that it can be readily collapsed by first removing the canvas covering and mat, and folding the side members, keel members and bow portions.

In Figure 12 is shown an oar composed of two main parts 44 and 45 hinged at 46 and provided with a keeper 47 for locking them in unfolded relation. The parts 44 and 45 can be folded by releasing the keeper and swinging them together on the hinge. This folding connection can be applied to a single or double oar.

What I claim is:

1. A collapsible canoe consisting of a pliant covering, a frame composed of rigid U-shaped ribs disposed at intervals throughout the length thereof, lengthwise members connecting the ribs one to another and being pivoted thereto, said members each being composed of a pair of bars linked together medially of their length for folding inwardly of the ribs, slots provided in the bars at the inner side of the link connection, a keeper pivoted in a slot of one of the bars and adapted to engage in the slot of the companion bar.

2. A collapsible canoe consisting of a pliant covering, a frame composed of rigid U-shaped ribs disposed at intervals throughout the length thereof, side members connecting the ribs one to another and being pivoted thereto, said members having medially disposed link joints to enable them to fold inwardly, keepers for locking the link joints to preclude folding, keel members connecting the ribs one to another and being pivoted thereto, said keel members having medially disposed link joints to enable them to fold upwardly, keepers for locking the link joints thereof to preclude folding, a bow extending from each extreme rib of the frame and pivoted thereto, each bow being composed of a pair of sections linked together, and a locking element fitted to one section so as to embrace the link connection of both sections to render them rigid.

OSCAR VALDEMAR K. HALD.
